United States Patent Office.

M. A. AVERY, OF GROTON, NEW YORK.

Letters Patent No. 74,788, dated February 25, 1868.

IMPROVED BUTT-HINGE.

The Schedule referred to in these Letters Patent and making part of the same.

TO ALL WHOM IT MAY CONCERN:

Be it known that I, M. A. Avery, of Groton, in the county of Tompkins, and State of New York, have invented a new and improved Butt-Hinge; and I do hereby declare that the following is a full, clear, and exact description thereof, which will enable those skilled in the art to make and use the same, reference being had to the accompanying drawings, forming part of this specification, in which—

Figure 1 represents a front view of a door hung on my hinges.

Figure 2 is a transverse section of the same, the line xz , fig. 1, indicating the plane of section.

Figure 3 is a longitudinal central section of the hinge detached.

Similar letters of reference indicate corresponding parts.

The object of this invention is to construct a reversible loose-jointed butt-hinge; one that will hang a door to swing to the right or to the left, and allow of lifting off the same, as ordinary butt-hinges, and which is smooth and even all round, in whatever position the door may be brought.

My hinge is composed of two halves, A and B. The half A, which fastens to the jamb, is provided with holes, which are countersunk both ways, so that it can be fastened to either side, for right or left, and the socket a , which supports the pivot b , is secured in the middle of the bracket A, projecting equally on either side. The other half, B, which fastens to the door, is provided with an eye, c , intended to catch over and turn on the pivot b of the half A. This eye is situated exactly in the middle of the length or height of the bracket B, so that said bracket can be secured to the door, either side up, without throwing it out of position. When the eye c is dropped on the pivot b , an open space is left between the top of the eye and an abutment, d , projecting from the top edge of the half A. This space is just high enough to allow of lifting off the door.

By the use of my hinge, all the trouble is avoided which arises from the use of the ordinary right-and-left-hand hinge, which, in many cases, compels the workman to run to the store and exchange his hinges, in order to get the door hung the way it is wanted. By my hinge the workman is enabled to hang the door as he may be desired to do, either right or left, and a hinge is obtained which is not liable to get out of order, which is cheap, and very convenient in its operation.

What I claim as new, and desire to secure by Letters Patent, is—

The right-and-left butt-hinge, having the screw-holes countersunk upon each side, when its leaf A is provided with an opening between the socket a and abutment d , for the application of the eye c , of the leaf B, as herein shown and described.

M. A. Avery.
